UNITED STATES PATENT OFFICE

111,906

DESIGN FOR A CHAIR

Kenneth F. Davis and John J. Josephs, Buffalo,
N. Y., assignors to The Sikes Company, Inc.,
Buffalo, N. Y.

Application July 7, 1938, Serial No. 78,336

Term of patent 14 years

To all whom it may concern:

Be it known that we, Kenneth F. Davis and John J. Josephs, citizens of the United States, residing at Buffalo, in the county of Erie and State of New York, have invented a new, original, and ornamental Design for a Chair, of which the following is a specification, reference being had to the accompanying drawing, forming a part thereof.

In the drawing:

The figure is a perspective view of the chair, showing my design.

We claim:

The ornamental design for a chair, as shown.

KENNETH F. DAVIS.
JOHN J. JOSEPHS.
